UNITED STATES PATENT OFFICE.

WILLIAM J. MCGUIRE, OF KEWANEE, ILLINOIS, ASSIGNOR TO WRAY'S FRESH WATER SYSTEM, OF KEWANEE, ILLINOIS, A CORPORATION OF ILLINOIS.

DEVICE FOR ELEVATING FLUIDS.

1,142,762.

Specification of Letters Patent.

Patented June 8, 1915.

Application filed July 7, 1913. Serial No. 777,766.

To all whom it may concern:

Be it known that I, WILLIAM J. MCGUIRE, a citizen of the United States, residing at Kewanee, in the county of Henry and State 5 of Illinois, have invented certain new and useful Improvements in Devices for Elevating Fluids; and I do hereby declare that the following is a full, clear, and exact description of the invention, which will enable 10 others skilled in the art to which it appertains to make and use the same.

This invention relates to a device for elevating fluid.

It pertains more particularly to a device 15 adapted to elevate fluids by air pressure.

One of the objects of the invention is to simplify water elevating devices by requiring but few parts.

Another object is to provide a valve in 20 control of and for directing air pressure to either of two receptacles for water to be elevated, and to include a motor in the path of the water from the discharge pipe in control of the valve by which said air pressure 25 is reversed in its flow.

Another object is to provide a water elevating device of an exceedingly simple form consisting of two receptacles for containing 30 water held under air pressure, a valve for directing air to one or the other of said receptacles, and to include in the water discharge pipe a motor having control of the valve, said motor being operated by the water drawn from the pipe to gradually 35 change the position of the valve, whereby in the action of the valve the air is directed to one or the other of the receptacles.

Another object is to provide a structure 40 which by reason of its simple structure and compactness can be lowered into the pipe or tube of a driven well.

In order that the invention may be readily understood I have provided the accompanying drawing, which is a sectional elevation 45 of my invention shown in a tube or pipe of a well.

A B indicate two immersed receptacles for water.

C is a pipe connected with each of the 50 receptacles for conveying water to a desired point or to fixtures, there being a faucet indicated at D, for example, as one of the outlets.

E F are foot valves, or check valves, in

the bottoms of the receptacles A B re- 55 spectively to admit water.

G is a vessel for receiving air there being a conduit H extending through it whose ends communicate with a discharge pipe J for air. The vessel G is made up of two 60 chambers G' and G² being separated by a partition K. This partition is provided with a bore L which communicates with a conduit H, a pipe M being threaded into said bore, as shown. In the said conduit H 65 at each side of the partition K is a series of apertures, one series being represented by N and the other by N'.

O is a pipe connecting the chamber G' with one of the receptacles, and P is a pipe 70 connecting the chamber G² with the receptacle B.

Q is a valve-rod extending into the conduit H and also extending outside the same through a suitable guide R its end within 75 the pipe being furnished with two spaced pistons S T together constituting a valve. The distance between the pistons is substantially equal to the distance between the two series of holes N, N', there being two 80 extreme positions of the valve thus formed. That is to say, the piston may lie below the two series of holes or above them. However, they also have intermediate positions as will be understood later herein. 85

U is a gear mounted on any suitable support not shown, and V is a connecting rod pivoted at one end on said gear and having attachment at its other end to the valve rod Q. 90

W is a motor of any suitable type to which the water discharge pipe C is connected and through which the water must pass before reaching its place of delivery. The shaft 2 of the motor is provided with a pinion 3 for example, which in turn meshes with a gear 4 which drives the gear U through a gear 5. However, I have merely illustrated this train of gears as one way of reducing the speed from the motor shaft to 100 the piston rod or valve rod. Other forms or arrangement can readily be provided. The gears may be suitably mounted on any form of support which I have not illustrated, and the motor may be a water wheel of any preferred structure that will rotate under any head of water whether very considerable or but very slight. 105

In operation it may be considered that water is being forced out of the receptacle A through the pipe C by air pressure the empty receptacle B being in the act of filling 5 with water through its check valve F. Air under pressure entering the conduit H from the pipe M is discharged through the lower series of holes N' into the chamber G' thence entering the pipe O and the receptacle A 10 keeping pressure upon the water in the latter. In order that water may enter the receptacle B a free outlet for air must be provided. In the position of the valve S T the air leaving B passes through pipe P into the 15 compartment G² and into the holes N in the conduit H and thence out through J. This condition prevails until sufficient water has passed from the receptacle A through the motor W to cause the gear U to be turned a 20 distance sufficient to move the valve S T to the other side of the series of holes N N' whereupon the direction of the air pressure from pipe M will be reversed. That is to say, it will then pass from the conduit H 25 into the compartment G² down through pipe P into receptacle B upon the water therein, while water will be permitted to enter A to fill it since the outlet for air from the latter will be through the pipe O into compartment G', conduit H, and finally out through 30 J. The time consumed in the travel of the valve S T has a certain relation to the time required to empty one of the receptacles A B, since a definite number of revolutions 35 of the motor caused by the amount of water passing through it in one emptying of a receptacle causes the change in the extremes of position of said valve. The delivery of the water through the pipe C, whether slow or 40 fast, operates the motor and the position of the valve is constantly changing so that by the time one of the receptacles is empty the valve must have reversed the direction of flow of air so that air pressure is then upon 45 the water in an opposite receptacle and as the movement of the valve must be quite slow I have provided the series of gears described so that the speed of rotation of the gear U having control of the valve will be 50 very slow indeed as compared with the speed of rotation of the pinion 3 of the motor. It is understood, however, that I may employ other ways or means of controlling the valve from the motor since the arrangement shown 55 is but one example of the manner in which it may be done, and I desire to state in employing the term "motor" I mean any device that will operate by water pressure, whatever its structure may be, for operating 60 the valve S, T. I may further state that I may adapt the structures herein described to the handling of other fluids for other purposes and furthermore I may control the valve S T by a motor operated by air pressure through the pipe M by certain arrange- 65

ments by which the automatic control of the water will result. I may also make various changes in the arrangement of my device without departing from the spirit and intent of the invention and the appended 70 claims and

Having described said invention, I claim:—

1. In a fluid elevating device, in combination, a pair of receptacles for the fluid to be elevated, a single conduit connected with both receptacles for the discharge therethrough of the fluid from either, a motor included with said conduit operated by the said fluid discharged through it, a compartment for air connected with one of the receptacles, a second compartment for air connected with the other receptacle, a conduit for introducing air pressure to both of the said air compartments, said conduit constituting a means for communication of both 80 the compartments with the outer air and including two apertures each opening into one of said compartments, and a valve to control the apertures, the same being adapted to place that part of the conduit for air 85 pressure in communication with one of the compartments through one of said apertures and to place the other compartment in communication with the outer air through the other part of said conduit. 90

2. In a water elevating device, in combination, a pair of receptacles for water, each including a check valve, a conduit for the discharge of water from both the said receptacles, a motor connected with the conduit, a separate compartment for air under pressure connected with each receptacle, a conduit adapted for supplying air to both of the compartments and including an opening into each, a valve in control of both openings 100 and operatively connected with the motor and adapted to direct air pressure alternately into the said compartments, and to alternately release air therefrom. 105

3. In a device for elevating water, in combination, a pair of receptacles for water each including a check valve, a conduit connected with and for discharging water from the receptacles, a motor included in the path of the water of said pipe, a pair of compartments for air under pressure, each connected with one of the receptacles, a conduit adapted for supplying air under pressure to the compartments, there being an opening for the discharge of air from each of the latter, 115 and a valve controlled by and operatively connected with the motor and adapted to direct the air into one of the compartments and release the air contained in the other compartment. 120

4. In a water elevating device, in combination, a pair of receptacles for water, a vessel for receiving air under pressure, including two compartments, a conduit connecting each of the compartments with one of the 130

receptacles, a conduit extending through both compartments and having communication with each of them, each said compartment having an escape outlet for air, and a 5 valve to open the outlet of one of the compartments and close communication between the other compartment and the said conduit.

5. In an apparatus of the class described, in combination, a pair of receptacles for 10 water, a conduit common to and for conducting water away from both of said receptacles, a motor in the path of the water in said conduit, a conduit for receiving and holding air under pressure and provided at 15 two places with an outlet, a separate receptacle for receiving air from said conduit through one of the outlets, each said receptacle communicating with one of the receptacles for water, a valve controlling both outlets 20 from said air conduit to the respective compartments and operated by and operatively connected with the said motor.

6. In a fluid elevating device, in combination, a pair of receptacles to receive the fluid 25 to be elevated including an inlet check-valve in each, a conduit connected with both receptacles for the discharge of water, a motor included in said conduit, a receiver divided into two separate compartments, a pipe connecting each compartment into one of the 30 receptacles, an air pipe extending through the receiver and communicating with both compartments, a valve in said pipe including two parts fixed relatively and operatively

connected with the motor, said valve in one 35 of its positions adapted to close communication between the air pipe and one of the compartments and open the other and in its other position to reverse the relation of the described parts.

7. In a device of the character described, the combination of two receptacles for water 40 each including a check valve, a conduit leading from and common to both receptacles, a motor included in the path of the discharge 45 through said conduit, a receiver including a dividing partition, a conduit extending through and opening outside of the two compartments of the receiver, said conduit including an opening within each compartment, an air supply conduit connected with 50 the last named conduit between the two openings, a valve stem extending longitudinally through the said air supply conduit and connected with the motor, and spaced 55 valves fixed on said stem adapted in the movement of the latter to alternately and simultaneously open communication of one of the compartments with the conduit to discharge outside the receivers, and open 60 communication of the outer compartment with the air supply conduit.

In testimony whereof I affix my signature, in presence of two witnesses.

WILLIAM J. McGUIRE.
